HYDRAULIC PLUG AND WHIPSTOCK

Filed Jan. 13, 1930

UNITED STATES PATENT OFFICE

HOWARD DUMM AND JAMES R. RUSSELL, OF LONG BEACH, CALIFORNIA

HYDRAULIC PLUG AND WHIPSTOCK

Application filed January 13, 1930. Serial No. 430,404.

This invention relates to a hydraulic plug and whipstock which is placed in an oil well when it is desired to cement a certain section thereof to check a flow of liquid, or to set a whipstock or similar operations. When a plug is to be subsequently drilled out, it is naturally desirable that a minimum amount of metal be placed in the plug so that the bit is not unduly hampered.

10 An object of our invention is to provide a plug of the character stated which is set at any desired point in the well by hydraulic pressure.

Another object is to provide a novel plug 15 of the character stated which will permit fluid to circulate therethrough while it is in place, or while it is being inserted in the well.

An advantage of our plug is that a whip- 20 stock can be attached thereto and this whipstock can be placed simultaneously with the plug. This results in a material saving in time and labor.

Other objects, advantages and features of 25 invention may appear from the accompanying drawings, the subjoined detailed description and the appended claims.

In the drawings

Figure 1 is a side elevation of our plug 30 with parts broken away showing interior construction.

Figure 2 is a longitudinal, sectional view of our plug.

Figure 3 is a longitudinal, sectional view 35 taken on line 3—3 of Figure 2.

Figure 4 is a side elevation of our plug and whipstock.

Figure 5 is a bottom plan view of the 40 sliding cam member.

Referring more particularly to the drawings, the numeral 1 indicates a cylindrical body member which is formed of wood so that it can be readily drilled out by subsequent operations of the bit. A fibrous packing disc 2 is secured to the top of the body 1 and this disc fits loosely within the casing and within the bore below the casing so that the plug can move freely downwardly under the pressure of the fluid on top of the

plug, all of which is usual and well known to those skilled in the art.

A bore 3 extends into the body 1 from the bottom thereof and the bore terminates adjacent the upper end of the body. A circulating pipe 4 extends into the body 1 from the top thereof and protrudes well into the bore 3. The pipe 4 is secured to the drill pipe in the usual manner and the circulation passes through this pipe and the drill pipe as will be further described.

A bell nipple 5 is secured to the pipe 4 and bears against the upper surface of the disc 2. The purpose of the nipple being to assist in supporting the pipe 4 and to keep this pipe from bending due to the weight of the pipe. The pipe 4 is secured in the body 1 by a pair of nuts 6—7 which screw on to the pipe and bear against the body.

A plurality of slots 8 are cut in the body 1 and extend through the body into the bore 3. A dog 9 is pivotally mounted in each of the slots and the outer surface of each of the dogs is serrated or notched so that the dogs will engage and securely grip the wall of the hole. A cam cylinder 10 is slidably mounted on the pipe 4 adjacent the lower end thereof, and the purpose of this cylinder is to engage each of the dogs 9 and rotate them outwardly so that they engage the wall of the hole to hold the plug in position.

A cup 11 is mounted below the cylinder 10 and engages the walls of the bore 3 so that there is no leakage past the cylinder when the plug is operated to actuate the dogs, as will be further described. A compressible closure member 12 is mounted in the lower end of the bore 3, and this closure member consists of an upper movable closure plate 13, a lower fixed plate 14, said upper and lower plates being joined together by a plurality of posts 15, each of said posts being surrounded by a coil spring 16, which springs press against the upper movable member 13 normally urging said member tightly against a bell housing 17, which housing is secured to the lower end of the pipe 4. A plate 18 partly closes the lower end of the body 1. A hole 19 is pro-

vided in the plate to permit circulation therethrough. A hole 20 is provided through the fixed plate 14 and a hole 21 is provided through the closure plate 13. A ball 22 closes the hole 21 and a cage 23 is secured to the plate 13 and limits the movement of the ball 22. The plate 13 rests against a shoulder 24, thus limiting the upward movement of the plate.

10 While the plug is being run into the hole, fluid is forced into the casing to push the plug downwardly, this fluid will pass around the plug to the bottom of the hole and then upwardly through the holes 19—

15 20—21. The ball 22 will be lifted and the fluid will pass upwardly through the pipe 4 into the drill pipe and thence to the surface. After the plug is lowered to the desired point, fluid under pressure is forced 20 into the drill pipe. The ball 22 is seated in the hole 21, the fluid acts upon the closure plate 13 and causes the plate to be depressed as shown in Figure 1. The fluid then escapes around the bottom edge of the bell housing 17 and then moves upwardly in the bore 3 and acts upon the cup 11 to force the cylinder 10 upwardly. The upward movement of the cylinder causes it to engage the dogs 9, which dogs are then swung 25 outwardly until they engage the wall of the hole and the plug is thus fixed in position. In order to retain the cylinder 10, in its raised position, we provide a spring latch 25 which latch drops into notches 26 on the exterior of the pipe 4. The plug is thus held immovable and the cement can be dropped thereon in the usual manner.

When setting a whipstock, present practice is to first lower the plug, then cement the 40 hole allowing the cement to dry a sufficient length of time, then drill out the cement to fit the whipstock, then insert the whipstock in the drill hole, again cement the whipstock in place, after which the cement must 45 again dry before the whipstock can be used. With our plug, a whipstock 27 can be secured to the upper edge of the body 1, preferably by screwing the whipstock on to the body. The whipstock is lowered simultaneously with the plug and one cement job is sufficient to secure the whipstock on place. Thus a material saving in time and labor results.

50 When our whipstock has been set in position in the hole as previously described, it can move neither upwardly nor downwardly. Also it is not difficult to release the drill pipe from the plug, and the plug will 60 not be moved during this releasing process. When the whipstock is used, it can be accurately placed in a known position by means of a surveying instrument, and the plug can be set and will be undisturbed by 65 any subsequent operations.

Having described our invention, we claim:

1. A hydraulic plug comprising a wooden body, said body having a central bore therein, a plurality of wall engaging dogs pivotally mounted in the body, dog engaging means slidably mounted in said bore, and conduit means extending into the bore whereby hydraulic pressure is exerted on the dog engaging means to actuate the same, to move said dogs into engagement with the wall. 75

2. A hydraulic plug comprising a wooden body, said body having a bore therein, a plurality of wall engaging dogs pivotally mounted in the body, a pipe extending into the bore, a cam cylinder slidably mounted on the pipe, said cylinder engaging the dogs, and valve means in said pipe whereby flow is permitted only upwardly through the pipe from the exterior of the plug. 80

3. A hydraulic plug comprising a wooden body, said body having a bore therein, a plurality of wall engaging dogs pivotally mounted in the body, a pipe extending into the bore, a cam cylinder slidably mounted on the pipe, said cylinder engaging the dogs, yieldably mounted closure means over the lower end of said pipe, said closure means having a hole therethrough, and a check valve in said hole. 85

4. A hydraulic plug comprising a wooden body, said body having a bore therein, a plurality of wall engaging dogs pivotally mounted in the body, a pipe extending into the bore, a cam cylinder slidably mounted on the pipe, said cylinder engaging the dogs, a movable closure plate bearing against the bottom of said pipe, said closure plate having a hole therethrough, a check valve in said hole and spring means yieldably urging said closure plate against the bottom of the pipe. 100

5. A hydraulic plug comprising a wooden body, said body having a bore extending partly therethrough, a pipe extending into said bore, a plurality of wall engaging dogs pivotally mounted in the body, said dogs protruding into the bore, a cam cylinder slidably mounted on the pipe within the bore, means on the cylinder engaging the pipe whereby the cylinder is held in dog engaging position, and yieldable closure means bearing against the lower end of the pipe. 110

6. A hydraulic plug comprising a wooden body, said body having a bore extending partly therethrough, a pipe extending into said bore, a plurality of wall engaging dogs pivotally mounted in the body, said dogs protruding into the bore, a cam cylinder slidably mounted on the pipe within the bore, means on the cylinder engaging the pipe whereby the cylinder is held in dog engaging position, a closure plate bearing against the bottom of the pipe, said plate 120

125

130

having a hole therethrough, a check valve in the hole, spring means bearing against the plate whereby it is yieldably urged against the bottom of the pipe.

5 In testimony whereof, we affix our signatures.

HOWARD DUMM.
JAMES R. RUSSELL.
